UNITED STATES PATENT OFFICE.

CHARLES BALL AND GEORGE LISPENARD, OF BROOKLYN, NEW YORK,
ASSIGNORS TO BALL & JEWELL, OF SAME PLACE.

DAMPER-REGULATOR.

SPECIFICATION forming part of Letters Patent No. 310,976, dated January 20, 1885.

Application filed August 20, 1884. (No model.)

To all whom it may concern:

Be it known that we, CHARLES BALL and GEORGE LISPENARD, citizens of the United States, and residents of Brooklyn, in the county of Kings and State of New York, have invented a new and useful Improvement in Damper-Regulators, of which the following is a specification, reference being had to the accompanying drawings.

10 The invention consists, essentially, in the combination, in a damper-regulator, with a hollow bed-plate and a water-chamber extending therefrom and adapted to contain water through which the pressure of steam is transmitted, of a lever fulcrumed to the said water-chamber, damper-connections attached to and capable of operation by said lever, and a motor-cylinder and piston connected with said lever and communicating with the hollow bed-plate.

15 The invention also consists in the combination, in a damper-regulator, with a hollow bed-plate adapted to contain water through which the pressure of steam is transmitted, of a lever and damper-connections to be operated thereby, an upright hollow piston-rod extending from and communicating with the bed-plate, and surmounted by a stationary piston, and a movable cylinder fitting the piston and connected with said lever for operating it.

20 The invention also consists in the combination, in a damper-regulator, with a lever and motor for operating it, of damper-connections attached to said lever, an eccentric or cam-shaped drum capable of rotation by the movement of said lever, and a weight suspended by a flexible connection from said eccentric or cam-shaped drum, and opposing a variable resistance to the movement of the lever.

25 The invention also consists in the combination, in a damper-regulator, with a lever and its operating-motor, of a concentric drum, and an eccentric or cam-shaped drum connected and capable of rotation together, connections through which said lever serves to rotate said drums and operate the damper, and a weight suspended by a flexible connection from the eccentric or cam-shaped drum, and opposing a variable resistance to the movement of said lever.

The invention also consists in certain details of construction, hereinafter described.

Figure 1 is a view, partly in elevation and partly in vertical section, of a damper-regulator constructed according to our invention. 55 Fig. 2 is a plan view of the same. Fig. 3 is a detail view illustrating some of the parts of said regulator most nearly connected with the damper.

Similar letters of reference denote corresponding parts in all the figures.

A designates the water-chamber; B, the bed-plate. The bed-plate and water-chamber are here shown as integral, being cast in one piece. The hollow of the water-chamber communicates with a cavity in the bed-plate at b'. This cavity extends from b' to h. At h is an upright hollow piston-rod, C, the interior of which communicates with the cavity in the bed-plate at h. This piston-rod may be screwed into the bed-plate or fastened in any convenient way. 65 A hollow piston, D, surmounts this rod, and is rigidly attached to its upper end. Surmounting both these is a movable cylinder, E, closed at its upper end, but open at its lower end. 70 The joint between the piston D and the interior of this cylinder is made tight with suitable packing material, and the parts are so arranged and constructed that there will be an uninterrupted connection from the chamber A 75 through the cavity in the bed-plate B, the hollow piston-rod C, and the hollow piston D to the space r in the cylinder E above said piston. The piston is here shown as provided with an ordinary cup-leather packing. a is the inlet-pipe, and a' the outlet-pipe, of said chamber A. 80 The drip-cup m is constructed and arranged to catch and retain any leakage of water or drops of grease that may come from the piston. 85

F designates a lever, which extends through nearly the entire length of the bed-plate. It is fulcrumed in the hinge-jaws e. These jaws are cast so as to be integral with and form a part of the water-chamber A. This lever is pivoted to the upper end of the cylinder E at 95 f, and extending thence is bent up at f' to accommodate the loop or link c, to which is fastened one end of the cord or strap c'.

H and H are two cylindrical drums fixed on the shaft b, which turns in suitable bearings 100

on the bed-plate B. Around one of these drums is wound the cord or strap c', with its inner end made fast to the periphery of the drum. The cord or strap I is wound in the 5 contrary direction around the other drum, and has its inner end also fastened to the periphery of the drum. Between these two cylindrical drums H and H, and fixed to the same shaft b, is an eccentric or cam-shaped drum, 10 G. Around this drum is wound the cord or strap d, one end of which is attached to the periphery of the drum, and the other end to the weight O. This eccentric drum is so arranged 15 that when the damper is open the cord or strap d will have its first point of contact with the drum where the radius of the drum is the shortest, as is illustrated in Fig. 1. The cord or strap I, passing from the drum H and running over the pulley K, extends to the wheel L, around 20 which it is wound and has its inner end fastened to the periphery thereof. This wheel L is mounted upon the shaft k of the damper P. This shaft turns in suitable bearings on either side of the smoke stack M. The wheel L is a 25 double-sheave pulley, in one groove of which is wound the cord or strap I, as aforesaid. In the other groove of said wheel, and in a contrary direction, is wound another cord or strap, I', which has one end fastened to the 30 periphery of the wheel and the other end to the weight N. The chain or cord g' is fastened to the bed-plate at g' and to the lever at g, to prevent too long a swing of the lever F. To use our invention, the parts are all arranged 35 as illustrated in Fig. 1. The chamber A, the cavity in the bed-plate, the hollow piston-rod C, and the space r are filled with cold water. Steam is then let on through the inlet-pipe a. It will then be found that as 40 the head of steam grows greater its increased pressure in the chamber A will cause a portion of the water therein to flow out through the cavity in the bed-plate and the hollow piston-rod into the space r in the cylinder. This will cause the cylinder to rise upward 45 and carry with it the lever F. As the lever F rises it unwinds the cord or strap C' from its one of the drums H. This winds up the cord or strap I on the other drum H. As the 50 cord or strap I is wound on the drum H it is unwound from the wheel L. This causes the damper P, which is on the same shaft with the wheel L, to turn in the chimney, and so regulate the draft. When the pressure of the 55 steam becomes less, the weights O and N, drawing in a direction contrary to the lever F, will return the various parts of the apparatus toward their original position. As the eccentric or cam-shaped drum G turns in winding up the cord or strap d, it presents to the

cord or strap in succession parts of its surface farther and farther from the center of motion. This gives the weight O gradually longer and longer leverage to resist the motion of the lever F.

65

What we claim as our invention, and desire to secure by Letters Patent, is—

1. In a damper-regulator, the combination, with a hollow bed-plate and a water-chamber extending therefrom and adapted to contain 70 water through which the pressure of steam is transmitted, of a lever fulcrumed to the water-chamber, damper-connections attached to and capable of operation by the lever, and a motor-cylinder and piston connected with said 75 lever and communicating with the hollow bed-plate, substantially as herein described.

2. In a damper-regulator, the combination, with a hollow bed-plate adapted to contain 80 water through which the pressure of steam is transmitted, of a lever and damper-connections to be operated thereby, an upright hollow piston-rod communicating with the bed-plate and surmounted by a stationary piston, and a movable cylinder fitting the piston and 85 connected with said lever for operating it, substantially as herein described.

3. The combination of the hollow bed-plate B and communicating water-chamber A, the damper-operating lever F, fulcrumed to said 90 water-chamber, the hollow piston-rod C, and stationary piston D, and the movable cylinder E, fitting the piston and connected with the lever, substantially as herein described.

4. In a damper-regulator, the combination, 95 with a lever and a motor for operating it, of damper-connections attached to said lever, an eccentric or cam-shaped drum capable of rotation by the movement of said lever, and a weight suspended by a flexible connection 100 from said eccentric or cam-shaped drum opposing a variable resistance to the movement of the lever, substantially as herein described.

5. In a damper-regulator, the combination, 105 with a lever and its operating-motor, of a concentric drum and an eccentric or cam-shaped drum connected and capable of rotation together, connections through which said lever serves to rotate said drums and operate the damper, and a weight suspended by a flexible 110 connection from the eccentric or cam-shaped drum and opposing a variable resistance to the movement of said lever, substantially as herein described.
